Attorney

UNITED STATES PATENT OFFICE.

HENRY W. MASON, OF NEW BEDFORD, MASSACHUSETTS.

HEATING FURNACE.

Application filed March 26, 1923. Serial No. 627,654.

To all whom it may concern:

Be it known that I, HENRY W. MASON, citizen of the United States, residing at New Bedford, in the county of Bristol and State of Massachusetts, have invented certain new and useful Improvements in Heating Furnaces, of which the following is a specification.

This invention relates to certain new and useful improvements in furnaces and pertains more especially to furnaces employed in the heating of dwellings.

The primary object of the invention is to provide a heating furnace which utilizes a maximum of the generated heat and one which is equally adaptable for use with either water or air.

A further object of the invention is to provide a furnace of simplified and economical construction, and one wherein lateral alternating or staggered fluid holding sections or conduits are provided, which project into the path of the ascending heat so as to necessitate tortuous travel of the latter from the fire chamber to the stack.

A still further object of the invention is to provide fluid containing or holding conduits which effect travel of the heated fluid horizontally in thin or film-like sheets throughout the depth of the furnace and substantially throughout the width thereof and to also provide interchangeable sections which can be easily applied in position and removed.

Another object of the invention is to provide a furnace in which the interior of the heat chamber is rendered freely accessible for cleaning purposes.

The invention has still further and other objects which will be later set forth and manifested in the course of the following description.

In the drawings:

Figure 1, is a front elevation of the invention, showing the heat chamber door open;

Figure 2, is a top plan view;

Figure 3, is a vertical sectional view;

Figure 4, is a section on line 4-4 of Figure 3;

Figure 5, is a rear end elevation of one of the fluid sections;

Figure 6, is a front elevation of one of the fluid-receiving sections, and

Figure 7, is a detail view of one of the joint-forming bushings.

In proceeding in accordance with the present invention, the opposed side walls of the furnace body are provided with series of spaced vertical water or air conduits 2, the ends of which conduits curve inwardly toward the interior of the heat chamber 3. As illustrated in Figure 3 of the drawings, the ends of the conduits in one side wall of the furnace body occur in horizontal planes 60 aligned with the central portions of the conduits of the opposed side wall. The lower ends of the lowermost conduits are provided with coupling nipples 4 and into which the water or air is conducted for heating, while the upper ends of the uppermost conduits are in register with ports 5 formed in the head or top 6 of the furnace. Nipples 7 for connection with distributing pipes are carried by the top 6, the pipes (not shown) 70 being connected to radiators, as usual. A smoke pipe 8 is also carried by the furnace top. In order to form air or water tight joints between the conduits and the outlet ports 5 of the head 6, nipples or bushings 75 9 are employed, the nipples having the opposite sides of their peripheries beveled from a meeting point central of the width of the rings and are fitted in countersunk portions corresponding to the beveled portions and formed in the furnace top and body sides as illustrated in Figure 3 of the drawings.

The adjacent ends of adjacent conduits are connected by fluid-receiving sections which embody a preferably horizontal approximately rectangular hollow casing having upper sides 10, lower sides 11, rear ends 12, front ends 12' a curved front 13 and an outer wall 14, the upper and lower sides 10 and 11 having central flared portions 15. The rear or outer walls 14 are formed with openings 16 and 17 which register with the flared portions 15. Nipples or bushings 18 similar to nipples 9, are also employed to effect a water or air-tight joint between the openings 17 and the curved ends of the conduits, as depicted in Figure 3 of the drawings.

The fluid receiving sections are also formed with central partitions or divisions plates 19, which terminate short of the curved front or inner ends of the sections, and which divide the latter into upper and

lower chambers to cause spreading of the water or air entering the sections, into relatively thin film or sheet like formation. The rear or outer walls 12 of the sections and 5 the division plates 19 are formed with perforated bosses 21, merging into the walls and plates, bolts 22 being employed and which are projected through the side walls 1 of the furnace body and into the bosses so 10 as to removably secure the sections in position.

The furnace body is preferably of approximately rectangular cross-section, and is provided with a hinged door 23 extending 15 over approximately the entire front of the heat chamber, so that by opening of the door the entire interior of the heat chamber is rendered freely accessible for purpose of cleaning or repair. In the latter regard it 20 will be noted that the sections are not only interchangeable but that same can be easily and quickly removed for purpose of cleaning the interiors thereof, or for the purpose of replacing burnt-out sections or ones 25 otherwise, through wear or defect, rendered unfit for further use.

The combustion chamber or fire box is closed by a door 25 the heat being produced by either wood, coal, gas or oil. The rear 30 end walls 12 of the sections closely abut the rear wall 30 of the furnace body, while the front end walls 12' thereof are engaged by the door 23.

In operation, water or air enters the conduits at the lower ends thereof and upon heating flows upwardly and entering the hollow lateral sections flows first beneath the division plates 19, thence above the latter and into the next adjacent conduit 2 which 40 path of travel is repeated until the heated fluid egresses from the ports 5 and then enters the distributing pipes. The fluid is thus given a vertical and horizontal path of travel, resulting in effectual heating 45 thereof. At the same time, the products of combustion must follow a tortuous path of travel from the fire box to the stack, same contacting not only with the vertical side walls of the furnace, but also with the lower 50 and then with the upper sides of the sections.

What is claimed is:—

1. In a heating furnace, a substantially rectangular body having a series of vertical 55 spaced conduits in two opposed side walls of the body, the adjacent ends of the conduits extending inwardly and opening through the inner side faces of the said walls, a series of hollow fluid-receiving sections for each of said walls having rear 60 ends abutting the rear wall of the furnace body and having outer walls abutting said opposed walls of the furnace body respectively, said outer walls of the sections having upper and lower openings registering

with the adjacent ends of adjacent conduits and the upper and lower sides of the sections having central flared portions registering with said openings respectively, a division plate in each section extending from 70 said outer walls thereof and between the upper and lower sides of the sections and spaced from the front walls of the sections, screw bolts extending from the outer faces of said opposed side walls into the sections 75 to hold the latter in place, and a door engaging the front ends of the sections.

2. In a heating furnace, a body having two series of opposed and horizontally arranged hollow fluid-receiving sections, the 80 sections of the series being staggered and connected at their rear portions to the respective side walls of the body and having their front portions spaced from the opposed side wall to form a vertical tortuous heat passage, division plates in the sections abutting the rear portions of the sections and spaced from the front portions thereof, and a series of spaced vertical conduits in each of the side walls of the body, the adjacent ends of adjacent conduits being in communication with the sections at the respective points above and below the division plates, and screw bolts extending from the outer faces of the body inwardly into engagement with the sections to hold the latter in position.

3. In a heating furnace, a body having a series of vertical spaced conduits in two opposed side walls of the body, the adjacent 100 ends of the conduits extending inwardly and opening through the inner side faces of the said walls, a series of hollow fluid-receiving sections for each of said walls having outer walls abutting said opposed walls of the body respectively, said outer walls of the sections having upper and lower openings registering with the adjacent ends of adjacent conduits and the upper and lower sides of the sections having central flared 105 portions registering with said openings respectively, a division plate in each section extending from said outer walls thereof and between the upper and lower sides of the sections and spaced from the front walls of the sections, and screw bolts extending from the outer faces of said opposed side walls into the sections to hold the latter in place.

4. In a heating furnace, a body having two series of opposed and horizontally arranged hollow fluid-receiving sections, the sections of the two series being relatively 120 staggered and connected at their rear portions to the respective side walls of the body and having their front portions spaced from the opposed side wall to form a vertical tortuous heat passage, division plates in the sections abutting the rear portions of the sections and spaced from the front portions thereof, and a series of spaced vertical 125 conduits in each section extending from said outer walls thereof and between the upper and lower sides of the sections and spaced from the front walls of the sections to hold the latter in place.

conduits in each of the side walls of the body, the adjacent ends of adjacent conduits being in communication with the sections at the respective points above and below the division plates and means to removably secure the sections in position.

5. In a heating furnace, a body having opposed series of hollow lateral fluid-receiving sections, the sections of the two series being relatively staggered, said sections each having upper and lower chambers communicating at their inner ends and the body having series of spaced vertical conduits with the adjacent ends of adjacent conduits 10 communicating with the respective chambers of the sections.

6. In a heating furnace, a body having spaced conduits in each of two opposed walls, two series of lateral hollow fluid-receiving sections carried by the body, the sections of the two series being relatively staggered and having upper and lower chambers which communicate at the inner ends of the sections, and means operable from the 20 furnace exterior to removably connect the sections to the body and with the adjacent ends of adjacent conduits communicating with the respective chambers of the sections.

7. In a heating furnace, a body having spaced conduits in each of two opposed walls, two series of lateral hollow fluid-receiving sections carried by the body, the sections of the two series being relatively staggered and having upper and lower chambers which communicate at the inner ends of the sections, and screw bolts extending 30 from the exterior of the body at points in

the space between the conduits inwardly into the sections to removably secure the latter in position.

8. In a heating furnace, a body, relatively staggered series of hollow sections carried by opposed walls of the body, said sections being of relatively narrow depth and having communicating chambers interiorly 40 thereof, and having ends which abut the respective back and front walls of the body and having fronts spaced from the adjacent opposed walls of the body and means to interconnect the adjacent chambers of adjacent sections of the respective series.

9. In a heating furnace, a body, relatively staggered series of hollow sections carried by opposed walls of the body, said sections being of relatively narrow depth and having communicating chambers interiorly 50 thereof, said sections having fronts spaced from the opposed wall of the body and extending throughout the depth of the body.

10. In a heating furnace, a body, relatively staggered series of hollow sections carried by opposed walls of the body, said sections being of relatively narrow depth and having communicating chambers interiorly 60 thereof, and having rear ends which abut the back and wall of the body and having fronts spaced from the adjacent opposed walls of the body, said body having an open front, and a door closing the front of the body and engageable with the front 70 ends of the sections.

In testimony whereof I affix my signature.

HENRY W. MASON.
